FEEDING MEANS FOR SEALING PADS FOR
RECEPTACLE CLOSURE CAPS

John A. Johnson, Woodhaven, N. Y.

Application March 15, 1933, Serial No. 660,863

5 Claims. (Cl. 113—113)

This invention relates to means for feeding sealing disks or pads by gravity to apparatus for assembling the disks in closure caps and particularly the stacking of the disks preparatory to the 5 delivery of the disks by gravity to the assembling apparatus whereby the assembling of the disks in the closure caps is greatly facilitated, and it is the principal object of the invention to provide feeding means for this purpose which is simple 10 and inexpensive in construction and efficient in use.

Another object of the invention is to provide 15 vibrating means to effect a proper stacking of the disks in juxtaposed relation and prevent the jamming of the disks during the delivery of disks from the stack to the assembling apparatus.

A further object of the invention is to arrange 20 the different operating parts for feeding the disks so that the parts are actuated from the same drive shaft.

In carrying out the invention there is provided 25 a casing to contain sealing disks for closure cap which casing may be arranged with a hopper inlet and a funnel shaped bottom having an outlet through the apex leading to a discharge tube arranged with a section fulcrumed at one end 30 in a fixedly supported section of the tube in which the disks are stacked and extending to means of closure cap assembling apparatus to feed the disks stacked in said tube section to closure caps, the end of the first tube section opposite its fulcrum support being adjacent the casing outlet and adapted to be reciprocated in a direction 35 transversely of the axis of the casing outlet to rock or vibrate said tube section on its fulcrum supported end to agitate and cause the disks to be properly stacked in contiguous superposed relation in the fixed tube section, the disks being agitated in the casing and alined with the casing outlet for delivery therethrough by a finger 40 continuously revolving in an orbit about the periphery of said outlet by the drive means of the tube reciprocating means.

In the drawings accompanying and forming a 45 part of this application, Figure 1 is an elevational view, partly in section, to show the means for agitating the disks in the casing and the means to vibrate the fulcrum supported tube section.

Figure 2 is a cross sectional view taken 50 substantially on the line 2—2 of Figure 1 looking in the direction of the arrows; and

Figure 3 is a longitudinal sectional view of the casing taken on the line 3—3 of Figure 1 looking in the direction of the arrows.

55 The embodiment of the invention illustrated

in the accompanying drawings is specially adapted to feed sealing pads for receptacle closure caps, comprising disks D of suitable yielding material, such as comminuted or solid cork, and in carrying out said invention there is provided a 5 circular casing 4 open and having an outwardly flaring flange portion 5 at the top for the releasable mounting of a hopper shaped member 6 to facilitate filling the sealing pads into the casing. The bottom portion of the casing is arranged 10 with a funnel shaped discharge outlet section 7 having a vertical wall portion 8 at the base thereof having a diameter equal to the diameter of the casing and said vertical wall portion 8 being releasably retained in abutting relation with 15 the lower edge of the casing wall by members 9 attached at one end on the casing wall and the opposite ends connected to the vertical wall portion 8 of the funnel outlet member by thumb screws passed through perforations in the members and screw threaded into said vertical wall portion 8, as at 10 in Figure 3, whereby the funnel shaped outlet section 7 may be readily disassembled from the casing 4 by removing the thumb screws. The apex end of the funnel shaped outlet section 7 is arranged with an outlet opening 20 having an annular member mounted therein, the opening in which member constituting the outlet opening and is slightly larger than the diameter of the disks D to be delivered from the casing, said member having an interior concave surface about the periphery thereof, as at 11 in Figure 1, to facilitate the directing and positioning of the disks D into register with the opening therein. Exterioly of the outlet opening the funnel section 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790

The casing is supported in elevated position relative to the closure cap assembling apparatus, so that the disks D are delivered by gravity to said apparatus, by a pillar or post 14, only the upper end of which is shown in Figure 1. A 45 bracket 15 is adjustably mounted on the post by a sleeve portion 16 of said bracket slidably engaged on the post and retained in adjusted position by a set-screw 17 threaded into the sleeve to abut the post and a set-screw 18 threaded in an extension of a collar 19 to have adjustment in a vertical direction to abut the end of the set-screw against the lower side of the bracket, the set-screw 18 being retained in bracket abutting and supporting position by a lock nut 20 threaded 55

onto the set-screw and abutting the underface of the extension of collar 19, the collar 19 being slidably mounted on the post 14 and retained in adjusted position by a set-screw 21. The bracket 5 15 is arranged with a boss 22 having an opening for the engagement of the tubular portion 13 of the funnel section 7 and said boss abutting the underface of the wall portion 12 of increased thickness of the funnel section to support the 10 casing by the bracket, the tubular portion 13 being releasably retained in the boss 22 by a set-screw 23 threaded into the wall of the boss with the free end engaging a recess in the exterior surface of the tubular portion 13 of the funnel 15 section, as at 24 in Figure 1.

To facilitate the delivery of the sealing pads or disks from the funnel section 7 through the opening 11, there is provided means to agitate and position the disks relative to outlet 11, comprising 20 a head 25 fixed to one end of a shaft 26 rotatably mounted in axial alinement with the opening 11 in an elongated bearing member 27 arranged at a right angle to a bar 28 extending transversely of the casing and relative to a channel wall 45 to 25 form a housing supported by the funnel section by one end resting on the top edge of said funnel section 7, as at 29 in Figure 1, and the opposite end of the bar 28 flanged and extended in juxtaposed relation to the vertical wall portion 8 of the 30 funnel section and adapted for the engagement of a bolt, as at 30 in Figure 1, to secure the housing formed by the bar 28 and channel wall 45 in position. The bearing member 27 is substantially the length of the shaft 26 to prevent the shaft 35 from being bent by stresses and strains of driving means applied to the end of the shaft opposite the head during the actuation of the agitator, as hereinafter described. The agitating and directing means comprises a finger 31 in the form of a 40 rod secured at one end, as by a screw threaded connection, in the head, as at 32, to project at an angle from the head with the free end portion of the rod bent to extend parallelly of the axis of the outlet opening 11 and the end beveled to correspond with the angle of inclination of the wall of 45 the funnel section 7, whereby said finger during the rotation of the head will revolve in an orbit about the opening 11 and thereby agitate and position the disks lying about the opening 11 into 50 register with said opening to drop therethrough by gravity, the head and the finger agitating and directing the disks toward the opening. It is to be understood that the head 25 may be arranged with a plurality of fingers 31 instead of one as 55 shown.

The head 25 is continuously rotated from a source of power, such as an electric motor, not shown, by a belt 33 (Figure 2) passed around a pulley on the motor shaft and a peripherally 60 grooved pulley 34 fixed on an end of shaft 35 rotatably supported in a pair of alined and spaced bearings 36 carried by brackets 37 mounted on and extending downwardly from the vertical wall portion 8 of the funnel section, as at 38 in Figures 65 1 and 3. The shaft 26 carrying head 25 is operatively connected to and driven from the shaft 35 by a belt 39 passed around a peripherally grooved pulley 40 fixed on the end of the shaft 26 extending above the bearing bar 28 and a similar pulley 41 fixed on the shaft 35 between the bearings 36, and over intermediate idler guiding pulleys 42 loosely mounted on a shaft 43 fixed and supported at the opposite ends in arms 44 extended upwardly from the brackets 37, as clearly 70 shown in Figure 3. The upper peripheral por-

tions of the pulleys 42 are in alinement with the pulley 40 at one end of the housing 45 to guide the belt 39 in a straight horizontal path to said pulley 40, as shown in Figure 1. The provision of the housing 45 prevents interference of the sealing pads in the casing with the travel of the belt 39, the housing 45 enclosing the driving means for the shaft 26 extending above the bearing bar and that portion of the belt traveling between pulleys 40 and 42, as clearly shown in 10 Figure 3.

To prevent longitudinal movement of the shaft 35 in its bearings 36 the pulley 41 is arranged with a hub extension 46, Figure 2, of a length whereby one side of the pulley and the end of the hub extension abut the opposite bearings and as said pulley is fixed to the shaft 35, said shaft cannot move longitudinally.

To prevent possible injury to the attendant of the apparatus a guard or housing is provided for 20 the pulleys 41, 42 and belt 39, consisting of a plate 47 removably attached to flanges 37' extended laterally from bearing brackets 37.

The sealing pads or disks D discharged from the casing by the revolving finger or fingers 31 25 are stacked in superposed relation in a tube 49 (Figure 1) for delivery to means for assembling in closure caps (not shown), said tube being mounted in a fixed position in an angle arm 50 fixed at one end to and extended downwardly 30 from the bracket 15 by bolts 51, the opposite end of the arm having a semi-circular recess for engagement of a side of the tube 49, and the tube being secured in the recess by a plate 52 having an intermediate semi-circular recess corresponding to the recess in the arm releasably mounted at the ends on the arm, as by bolts 53, with the recess in said plate engaging the opposite side of the tube 49 and clamping the same to the arm 50, as clearly shown in Figure 1. The tube 49 is 40 arranged with a longitudinal sight slot 54 to inspect and readily ascertain the quantity of disks in the tube.

To properly stack the disks D in the delivery tube 49 in flat horizontal position whereby the 45 disks may readily slide down the same and be delivered to the means for assembling the pads in the caps in proper horizontal position, and also prevent the jamming of the disks in the tube by the disks assuming an angular position relative to the horizontal, the delivery tube is adapted to agitate the disks as they are discharged therein from the casing by vibrating the entrance end of the tube. This vibrating of the tube is accomplished by terminating the entrance end 55 of tube 49 in spaced relation to the casing outlet 11 and the tubular extension 13 of the funnel member 7 and providing a section of tubing 55 of a diameter substantially equal to the diameter of tube 49 loosely supported in an enlarged 60 annular seat formed in the entrance end of the discharge tube 49 by annularly increasing the diameter of said end of the tube to arrange a shoulder for the engagement of an end of the tubing 55, as at 56 in Figure 1, thus in effect 65 forming a fulcrum support for the tubing 55 upon which it may be rocked and vibrate the tubing. The fulcrum supported tubing 55 is of a length to extend from its fulcrum support 56 into the tubular portion 13 adjacent to the outlet member 70 11 with the end of the tubing adjacent said outlet member flanged laterally in parallel relation to the exterior peripheral wall portion about the outlet opening, as at 57, to facilitate the entrance of the disks into the tubing 55 during the vibrat- 75

ing of said tubing. The diameter of the tubing 55 is less than the diameter of the bore of the tubular portion 13 to permit the tubing to be rocked without interfering with the wall of said tubular portion.

The tubing 55 is rocked by moving the flanged end 57 thereof transversely of the casing outlet 11, said end being normally urged to position laterally of the outlet opening. The means to rock the tubing 55 comprises a rod 58 slidably mounted in a portion 59 of reduced diameter of a bore 60 extended horizontally into the wall portion of increased thickness 12 of the funnel section 1 to an annular enlargement 61 of the bore of the tubular portion 13 at the juncture thereof with the casing outlet 11. The inner end of the rod extending into the annular enlargement 61 is reduced in diameter and engages a correspondingly formed recess, as at 62, in a ring 63 loosely 20 encircling the tubing 55 in abutting relation to the tubing flange 57 and within the annular enlargement 61 of the tubular portion 13. The rod 58 is yieldingly urged toward the ring 63 by a spring 64 coiled about the rod with one end abutting an annular shoulder 65 extending laterally of the rod intermediate the ends thereof and the opposite end of the spring engaging a cover plate 66 for the bore 60 having a cylindrical portion 67 in alignment with the bore 60 for the slid- 30 able engagement of the outer end of the rod 58 to form a bearing support therefor, the cover plate being releasably secured to the wall portion 12 by screws 68, Figure 1. The shoulder 65 of the rod 58 is arranged at a distance from the 35 rod connection 62 with the ring 63 to permit movement of the rod to position the ring in contiguous relation to the wall portion of the enlargement 61 of the tubular portion 13 diamet- 40 rically opposite the reduced bore portion 59 and position the flanged end of the tubing 55 in one of its extreme lateral positions, the shoulder 65 acting as a stop limiting this movement of the rod 58 and properly positioning the tubing laterally of the outlet opening 11. The flanged end of 45 the tubing 55 is intermittently actuated laterally in a direction toward the rod 58 against the tension of spring 64 by a plunger 69 having the opposite end portions of different diameters slidably mounted in a bore 70 extended horizontally 50 through the wall portion 12 in alignment with the bore 59, 60, and having two diameters corresponding to the plunger 69 with the portion of larger diameter having a key connection with the plunger, as at 71, to prevent turning but 55 permit reciprocation of said plunger. The end of smaller diameter of the plunger 69 is connected to the ring 63 in opposed relation to the connection 62 of the rod 58 with the ring and in a manner similar to said connection, as at 72. 60 The plunger 69 is periodically moved toward the tubing by a multiple cam faced wheel in the form of hexahedral disk 73 mounted on the hub extension 46 of the pulley 41 juxtaposed to the pulley 41, and secured to said pulley by screws 74, 65 whereby the disk is rotated simultaneously with the agitating finger 31. The corners of the disk which are squared, as at 75, are successively engaged with a roller 76 rotatably mounted in a bifurcated portion 77 extended from the end of a larger diameter of the plunger 69 and thereby 70 imparting longitudinal movement to the plunger against the tension of spring 64, the roller 76 following the cam edge of disk 73 under the influence of the spring 64. By the movements of 75 rod 58 and plunger 69 the tubing 55 is continu-

ously reciprocated or vibrated on its fulcrum support 56, and by this vibrating movement of the tubing the disks D therein are agitated and stacked in contiguous relation to each other, as clearly shown in Figure 1. The inner face of the 5 ring 63 is of convex form in cross section to permit of lateral movement of the tube therein.

It will be obvious that various modifications may be made in the structure and arrangement of parts without departing from the scope of the 10 invention.

Having thus described my invention, I claim:

1. In feeding means for sealing pads for receptacle closure caps, a hopper having a funnel shaped bottom with an outlet through the apex thereof having a diameter slightly greater than the pads, means rotatably supported in the hopper co-axially of and above the outlet and extending adjacent to the bottom concentrically of and revoluble about the hopper outlet to agitate 20 and effect delivery of the pads through the hopper outlet, a tube having a diameter less than the hopper outlet and slightly greater than the pads and a fulcrum support at one end axially of the outlet and the opposite end juxtaposed to the 25 hopper outlet to receive pads therefrom, a yieldably mounted rod connected to the end of the tube juxtaposed to the hopper outlet and yieldingly urging said end of the tube in one direction to predetermined position laterally of the 30 hopper outlet, a plunger connected to the tube diametrically opposite to said rod, and means to intermittently actuate the plunger and move the tube in a direction opposite to and against the yielding force of the rod to impart vibratory 35 movement to the tube and effect a stacking of the pads in the tube delivered through the hopper outlet.

2. Feeding means for sealing pads for receptacle closure caps as claimed in claim 1, wherein 40 the actuating means for the plunger comprises a disk rotatable in a plane coincident with the axis of the plunger having multiple cam faces about the periphery to co-operate with said plunger.

3. In feeding means for sealing disks for receptacle closure caps, a hopper having a funnel shaped bottom with an outlet through the apex thereof, a tube fulcrumed at one end co-axially of the outlet with the opposite end contiguous to the bottom of the hopper and communicating 50 with the hopper outlet to receive disks therefrom, a ring loosely engaged on the end of the tube contiguous to the hopper outlet, yielding means to normally exert a force on the ring to rock the tube on its fulcrum support and position the end 55 of the tube communicating with the hopper outlet to one side of said outlet, and reciprocatory means connected to the ring in opposed relation to the yielding means adapted to rock the tube and move said end of the tube transversely to 60 the opposite side of the hopper outlet against the force of the yielding means and thereby agitate the disks delivered into the tube and effect a stacking of the disks in superposed relation in 65 the tube.

4. In feeding means for sealing pads for receptacle closure caps, a casing having a funnel-shaped bottom and an outlet through the apex thereof having a diameter slightly greater than the pads, means in the casing revoluble about 70 the outlet on an axis co-axially of the outlet to agitate and cause delivery of the pads through the outlet, a tube supported to have movement at one end co-axially of the outlet with the opposite end juxtaposed to the casing outlet to receive 75

- the pads therefrom, means to yieldingly urge said end of the tube in a direction laterally of the outlet, and means to intermittently impart movement to the tube against said yielding means in the opposite direction laterally of the outlet to vibrate the tube and thereby effect a stacking of the pads therein.
5. In feeding means for sealing pads for receptacle closure caps, a hopper having an outlet at the bottom thereof, means rotatably mounted in the hopper on an axis co-axially of the hopper outlet and arranged to agitate and cause delivery of the pads through the outlet, a tube sup-
10. 5. In feeding means for sealing pads for receptacle closure caps, a hopper having an outlet at the bottom thereof, means rotatably mounted in the hopper on an axis co-axially of the hopper outlet and arranged to agitate and cause delivery of the pads through the outlet, a tube sup-

ported at one end co-axially of the hopper outlet with the opposite end juxtaposed to the hopper outlet to receive the pads therefrom, means to yieldingly urge said opposite end of the tube in a direction laterally of the hopper outlet, means to impart intermittent movement to the tube against said yielding means in the opposite direction laterally of the outlet to vibrate the tube and effect a stacking of the pads therein, and means to simultaneously rotate the pad agitating 10 means in the hopper and actuate the tube vibrating means.

JOHN A. JOHNSON.
